UNITED STATES PATENT OFFICE.

RAY P. VASTINE, OF CHICAGO, ILLINOIS, ASSIGNOR TO GEORGE M. VASTINE, OF CHICAGO, ILLINOIS.

OBSERVATION WINDOW FOR FURNACES.

Application filed August 24, 1925. Serial No. 51,959.

This invention relates to a device for permitting the interior of a furnace or the like to be viewed from without, without necessitating the opening of any doors or closures. It is particularly desirable to view the interior of furnaces or the like to ascertain the character of the combustion or the manner in which the heat therein is effecting the elements being treated without having 5 to open a door or a peep hole, as such opening causes a loss in efficiency due to either the cold draft on the heated parts in the furnace or a flare back of the heat from said furnace. Ordinarily no transparent material 10 such as glass will stand the high heat of the furnace in order to permit its use in a device of this kind. In my copending application, Serial No. 746,962, I described a manner in which the heat might be so reduced 15 near the exterior of the opening in a side of the furnace so that glass or similar substance might be used in said opening for the closure thereof.

It is an object of this invention to provide 20 an improved means for reducing the heat near the exterior of the opening.

It is further an important object of this invention to provide a device of the class described in the above mentioned copending 25 application which will provide a maximum view of the interior of the furnace.

It is also an object of this invention to provide a device of this type which is simple and rugged, which may be economically 30 manufactured and conveniently installed and used.

It is further an important object of this invention to provide a device of this type having a forced draft circulation for reducing the heat transferred to the outer end 35 of the observation passage.

Other and further important objects of this invention will be apparent from the disclosures in the specification and the accompanying drawings.

This invention (in a preferred form) is illustrated in the drawings and hereinafter more fully described.

On the drawings:

Figure 1 is a detail side elevational view of a device embodying this invention, with parts omitted and detached from the furnace.

Figure 2 is an enlarged horizontal frag-

mentary section with parts removed taken at 55 the line II-II of Figure 1.

Figure 3 is an enlarged fragmentary front elevational view with parts omitted of the device shown in Figure 1, showing the same attached to a furnace.

Figure 4 is an enlarged vertical longitudinal fragmentary section with parts omitted taken at the line IV-IV of Figure 3.

Figure 5 is a transverse vertical section with parts omitted taken at the line V-V 65 of Figure 4.

Figure 6 is a detail enlarged fragmentary vertical transverse section with parts omitted taken at the line VI-VI of Figure 4.

Figure 7 is a side elevational view of a 70 modified form of the device embodying this invention showing the same in position in the side of the furnace.

Figure 8 is a vertical longitudinal fragmentary enlarged section with parts omitted 75 of the device shown in Figure 7.

Figure 9 is an enlarged detail fragmentary view with parts omitted of means for automatically controlling the flow of air around the outer glass plates of the device.

Figure 10 is an enlarged detail horizontal fragmentary sectional view taken at the line X-X of Figure 8 with parts omitted.

As shown on the drawings:

Referring to Figure 1 which illustrates a device embodying this invention for use on furnace doors, there is shown a hollow outer casing 1 of rectangular flaring cross section which diminishes the intensity of radiation from the furnace as well as increases the view obtainable therethrough. The casing 90 1 is provided with transverse integral annular ribs 2 on its exterior to provide a greater surface to radiate the heat conducted through the walls thereof. The outer end of the casing 1 is provided with an integral flange 3 and the inner end of said casing is provided with an integral annular flange 4. An annular supporting member 5 receives

therein on the right side thereof flange 3 and on the left side thereof it receives a 100 rectangular shaped rim 6. Suitable bolts 6' (Figure 3) extend through the rim 6, the annular member 5 and the flange 3 for clamping said annular member between said rim and said flange. At the upper end of 105 the rim 6 is a pair of forwardly extending integral supports 7 which pivotally support

in juxtaposed relation outer and inner doors or frames 8 and 9 respectively. The annular member 5 is constructed to hold the flange 3 and the rim 6 longitudinally spaced 5 apart within said member.

The flange 3 at the bottom edge thereof is cast rearwardly to provide a recess to receive a horizontal semi-cylindrical flange 11 integral with the bottom of the annular member 5 and for providing with said flange an enlarged chamber 10 in which to receive the end of a bolt 12. The bolt 12 extends through a suitable aperture in the lower edge of the rim 6 through a recess in the 10 upper edge of a vertically extending integral portion 13 on the annular member 5 and into said chamber 10. Integral with the annular member 5 and communicating with the chamber 10 is a hollow portion 14. The 15 portion 14 is flanged at its bottom edge and is provided with bearing members near its lower edges for supporting a transversely extending rod 15 (Figure 6) which has pivotally mounted thereon a circular closure plate 16. The plate 16 is balanced by an integral arm 17 which is deflected out of the plane of said plate. When the plate 16 is closed, the arm 17 will extend upwardly and when the plate 16 is open, the arm 17 20 will assume a horizontal position. Secured to the flange on the lower edge of the portion 14 is a plate 18. The plate 18 is provided with a circular aperture 19 on the right side thereof as viewed in Figure 6 which 25 when the plate 16 is closed, communicates with the bottom side of the latter and is closed thereby. The plate 18 is also provided with an integral hollow cylindrical member 20 communicating with the interior 30 of the portion 14 by a suitable opening in said plate beneath the arm 17 so that when the latter is in horizontal position it will abut the plate 18 at the left edge of said opening.

Extending inwardly from the rim 6 integral therewith and communicating with the outer side thereof by a central opening therein is an inner casing 21 spaced from the outer casing to provide a space or passage 35 therebetween for the circulation of a cooling medium. The casing 21 converges from its outer end to its inner end in the same manner as the outer casing 1 and is of rectangular cross section, the sides thereof being substantially parallel to the sides of the outer casing 1. Longitudinal outwardly extending integral ribs 21' are provided on the sides of the casing 21. Extending across the outer opening of the inner casing 21 is 40 a grid 22, which tends to further decrease the radiation toward the glass without materially obstructing observation therethrough of the interior of the furnace. Flanges 23 are provided on opposite vertical sides of 45 the grid 22 for securing said grid to the rim

6. Extending across the inner end of the casing 21 is a smaller grid 24 of similar construction which is mounted in suitable recesses in the inner edge of the casing 21, and which is held in position by an inwardly 70 extending annular integral flange 25 on the casing 1, said flange extending very nearly to the inner edge of the casing 21. The casing 21 is provided with a plurality of radially extending apertures 26 near its inner 75 end.

The inner frame 9 has mounted therein a rectangularly shaped glass or substantially transparent plate 27 which is aligned with the grids 22 and 24 but which is considerably 80 larger in area than the outer end of the casing 21. The frame 9 is also provided with a horizontal transverse aperture 28 in its upper portion and a similar aperture 29 in its lower portion. The rim 6 is formed with a recess 30 communicating with the aperture 29 and having its edges snugly fitting the inner edges of the latter. A horizontal transverse aperture or port 31 in the rim 6 connects the recess 30 with the chamber 10.

Surrounding the bolt 12 at its inner end is a compression spring 32 held against rearward movement on said bolt by a diametrically positioned pin 33 in the end of said bolt. A washer 34 surrounds the bolt 12 inwardly of the upwardly extending portion 13 and is abutted by the forward end of the spring 32. A suitable dog 35 is formed on the outer end of the bolt 12 and is adapted to engage with depending lugs 36 on the lower edge of the outer frame 8 for holding both frames closed against the rim 6. The outer frame 8 has mounted therein a rectangularly shaped glass plate 37 which is of somewhat larger area than the plate 27. The plates 27 and 37 are spaced apart to provide a passage for the circulation of a cooling medium as explained hereinafter.

Rotatably secured on the lower end of the cylindrical member 20 is one end of an elbow connection 38. Rotatably secured on the other end of the connection 38 is a hollow cylindrical member 39 which slidably receives a second hollow cylindrical member 110 40. The latter is rotatably secured to one end of a second elbow connection 41. The second elbow 41 has rotatably secured thereto at the other end thereof a cylindrical member 42. The member 42 is rigidly secured 115 to a flange 43.

The device may be connected to a furnace as shown in Figure 1, the flange 4 being secured to the outer wall of said furnace. The 120 wall of the furnace should be apertured to communicate with the interior of the casing 1, said aperture diverging from beneath the flange 4 toward the interior of the furnace. The flange 43 may be connected to any suitable support or may be secured to 125 130

the side of the furnace. A cooling medium, air, for instance, may be forced up through the flexible connection comprising the members 38 to 42 inclusive and the member 20 for entering the hollow portion 14 by connecting the cylindrical member 42 to a separate blower, or in case the closed ash pit system of forced draft is used by connecting said member 42 to the ash pit. In case the closed fire room system of forced draft or natural draft is used, the air may enter the portion 14 through the aperture 19, the plate 16 being light enough to be lifted by the air. From the interior of the portion 14 the air will flow upwardly into the chamber 10, some of it flowing rearwardly around the outer periphery of the inner casing 21 and over the rear edge of the latter through the grid 24 into the furnace. Some of the air which flows rearwardly around the outer periphery of the casing 21 will flow through the holes 26 into the interior of said casing and thence through the grid 24 to the furnace. A large portion of the air will flow through the aperture 31 to the aperture 29, thence between the plates 27 and 37 through the aperture 28 and downwardly past the rear side of the plate 27. From the rear side of the plate 27 the last mentioned portion of air will flow through the grid 22 into the casing 21 and out through the grid 24 to the furnace.

In Figures 7 to 10 inclusive there is shown a modified form of the device. In this form an outer casing 44 of rectangular cross section is provided, said casing having longitudinal outwardly extending ribs 44' on the sides thereof. The casing 44 extends into a suitable converging recess 44^a in the side of the furnace wall. An inwardly diverging aperture 45 in the furnace wall communicates with the inner end of the recess 44^a. The outer end of the casing 44 is provided with an annular flange 46 having an integral forwardly extending rim 47 on the outer periphery thereof. A rectangularly shaped rim 48 is suitably secured to the outer end of the casing 44 within the rim 47 and spaced from the flange 46 by means of a shoulder (not shown) in the latter to form with said flange and said rim 47 an annular recess.

Connected to the bottom side of the flange 46 and the rim 48 and communicating with the above mentioned annular recess contained therebetween is a removable box 49 containing a valve such as that shown in Figure 6. The valve in the box 49 may communicate with either a separate forced draft means or the atmosphere in the fire room as desired in the same manner as in the previous embodiment.

Rearwardly extending from the rim 48 and integral therewith is a rectangular cross sectioned inner casing 50 having longitudi-

nal outwardly extending ribs 50' thereon. The inner casing 50 is aligned with the outer casing 44 and is spaced therefrom. An outer grid 51 is provided at the forward end of the inner casing as in the previous embodiment. An inner grid 51^a is also provided at the inner end of the casing 50. Forwardly extending lugs 52 are provided at the lower edge of the rim 48 for supporting a shaft 53 on which are pivoted an inner and an outer door or frame 54 and 55 respectively. The frames 54 and 55 are provided with glass plates 54' and 55', respectively, similar to the plates 27 and 37 respectively of the previous embodiment. A pair of forwardly extending bolts 56 are oppositely supported at the upper sides of the rim 48 by means of a pair of apertured laterally extending ears 57 on said rim. Rearwardly positioned from each ear 57 and aligned therewith is an ear 58 secured to the rim 47. Compression springs 59 surrounding each bolt 56 are compressed between the ears 57 and 58. A washer 60 is mounted on each bolt 56 between the forward end of its respective spring and ear 57. A diametrical pin 61 extends through the end of each bolt and is abutted by the rear end of its respective spring for holding said bolts rearwardly against said ears 58. Dogs 62 on the forward ends of the bolts 56 engage with lateral lugs 63 on the outer frame 55 for holding the same in closed position.

The inner frame 54 is provided in its lower side with a horizontal transverse aperture 64 and in its upper side is provided with a similar aperture 65. The rim 48 is provided with a recess 66 adjacent the aperture 65 and has a plurality of apertures or ports 67 extending therethrough communicating with said recess. A transverse rod 68 is supported inwardly of the apertures 67 in a pair of oppositely disposed guide members 69 secured to the inner side of the rim 48 by flanges 70. The guide members 69 have sloping recesses 71 therein for permitting the rod 68 when released to slide downwardly in said recesses and close the apertures 67. A pair of rearwardly extending pins 72 secured to the frame 54 and normally extending through the recesses 66 and apertures 67 is adapted to hold the rod 68 away from said apertures 67 when said frame is in closed position. A removable plate 73 is adapted to close an opening between the forward upper edge of the rim 47 and the upper edge of the rim 48. The outer frame 55 is provided with a horizontal transverse recess 74 adjacent the outer end of the aperture 65 and a similar recess 75 adjacent the outer end of the aperture 64. The rim 47 at the vertical edges thereof is provided with a pair of apertures which are normally closed by means of removable plates 76. The air may flow up through the box 49 into the space between

the inner and outer casings past rod 68 through the apertures 67, the recess 66, the aperture 65, the recess 73, downwardly between the glass plates in the frame 54 and 55, past the recess 74 through the aperture 64 upwardly past the inner face of the glass plate in said frame 54, through the grid 51 and into the furnace in opposition to the thermal radiation therefrom. If the frames 10 are opened, the pin 71 secured to the frame 54 will allow the rod 68 to close the apertures 67 and thus prevent the flow of air through said apertures, thus protecting anyone who might open said frames from a flare 15 of hot air through said apertures, without discontinuing or affecting the flow of the cooling air thru the supporting casing. In case natural draft is used, the flow of air may be increased by removing the plates 72 20 and 75 and even the box 49 and connections thereto. It will be apparent to those engaged in the operation and construction of furnaces and the like that I have provided a device which may be economically manufactured, easily installed and used for efficiently observing and controlling the operation of said furnaces.

I am aware that many changes may be made, and numerous details of construction 30 may be varied through a wide range without departing from the principles of this invention, and I therefore do not purpose limiting the patent granted hereon, otherwise than necessitated by the prior art.

35 I claim as my invention:

1. In a device of the class described, a casing, a second casing within said first casing, a pair of separately movable transparent doors supported at the outer end of one 40 of said casings for normally closing the same and means for admitting air to the space between said casings, there being means communicating with said space for circulating air between said doors.

45 2. In combination, a combustion chamber enclosure having an opening therethrough, heat reducing means in said opening, and a plurality of separately movable observation closures hingedly mounted to normally close the outer end of said means.

50 3. In a device of the character described, a pair of spaced casings, and a pair of independently movable closures pivotally mounted on the outer end of one of said casings to normally close the same.

55 4. In a device of the character described, tubular means, a plurality of grids graduated with respect to their planar areas spaced in said tubular means, a transparent closure for said tubular means, and means for admitting a cooling medium through said grids from passages individual to said grids.

60 5. An observation device for combustion chamber enclosures including comprising an

outer casing, an inner casing spaced from said outer casing, said inner casing having an open inner end, a grid disposed in the outer end of said inner casing, a grid disposed in the inner end of said outer casing, and an 70 observation closure for one of said casings.

6. In combination, a furnace including a wall having an opening therein, a tubular spaced member disposed in said opening, and an observation closures for said member 75 supported by and spaced from the inner walls of said member, said closures having an air passage disposed in communication with the interior of said member.

7. In a device of the class described, an outer casing, an inner casing spaced from said outer casing to provide an air passage therebetween, a pair of hinged transparent closures for the outer end of one of said casings, said closures being spaced apart to provide an air passage therebetween in communication with said first-mentioned passage, and means responsive to the opening of said closure for cutting off the communication between said passages. 80

8. In a device of the class described, a casing, a second casing disposed within and spaced from said first-mentioned casing to provide an air passage therebetween, an annular outwardly extending rim on said second casing, a pair of observation closures hinged to said rim, said closures having a second air passage therebetween, said rim having apertures therethrough establishing communication between said air passages, a 90 rod in inclined supports, and means connected to said closures to hold said rod away from said apertures when said closures are closed and to permit said rod to close said apertures when said closures are opened. 100

9. In a device of the class described, a first and outer casing, a second casing partially disposed within said outer casing and spaced therefrom to provide an air passage therebetween, a pair of observation closures 110 hinged to one of said casings adjacent the outer end thereof, said closures being spaced apart to provide an air passage therebetween in communication with said first-mentioned air passage, resilient means to maintain said closures in closed position, and means communicating with said passages permitting the use of either natural or forced draft. 115

10. In combination, a combustion chamber enclosure having an opening therethrough, a casing communicating with the interior of said chamber through said opening, a second casing in said first mentioned casing and spaced therefrom to provide an air passage therebetween, means for admitting air to said passage, a pair of substantially transparent closures adjacent the outer end of one of said casings, said closures defining an air space therebetween, said air space being in communication with said passage and 120 125 130

means for automatically closing off said communication when said closures are opened.

11. In combination, a combustion chamber enclosure having an opening therethrough, a casing extending into said opening, means for maintaining said casing in spaced relationship to the walls of said opening, means for admitting a cooling medium in the space between said casing and said walls, a pair of movable closures adjacent the outer end of said casing, said closures having a space therebetween for the circulation of a cooling medium, said spaces being in communication with each other, and means cutting off said communication when said closures are opened.

12. In combination, a combustion chamber enclosure having an opening therethrough, a casing extending into said opening, means for supporting said casing in spaced relationship to the walls of said opening, a substantially transparent closure for said casing, and means for admitting a cooling medium between said casing and said walls and to said combustion chamber through a plurality of paths.

13. In a device of the character described, nested casings in spaced relationship, a plu-

rality of apertured grids in said casings, 30 said grids decreasing in their planar areas in an inward direction, a substantially transparent pair of movable closures for one of said casings having a space therebetween in communication with the space between said 35 casings, means for admitting a cooling medium into the space between said casings, and means responsive to the opening of said closures for cutting off said cooling medium from the space between said closures. 40

14. In a device of the character described, a pair of substantially nested casings, the inner casing substantially closing the outer end of the outer casing, and a plurality of independently movable closures pivoted to 45 the outer portion of said inner casing.

15. In a device of the character described, a pair of substantially nested casings spaced apart to provide a passage therebetween, a pair of observation closures hinged to one 50 of said casings for closing the outer end thereof, said closures having a passage therebetween in communication with said first mentioned passage, and means for admitting a cooling medium into one of said passages. 55

In testimony whereof I have hereunto subscribed my name.

RAY P. VASTINE.
